UNITED STATES PATENT OFFICE.

FRANK GRANT, OF WESTFIELD, MASSACHUSETTS.

HOLDER FOR STICK MATERIAL.

1,306,179.

Specification of Letters Patent. Patented June 10, 1919.

Application filed November 9, 1918. Serial No. 261,839.

To all whom it may concern:

Be it known that I, FRANK GRANT, a citizen of the United States of America, residing at Westfield, in the county of Hampden and 5 State of Massachusetts, have invented certain new and useful Improvements in Holders for Stick Material, of which the following is a specification.

This invention relates to improvements in 10 holders for stick material and more particularly to improved containers for material, such as shaving soap and the like, which containers are provided with feeding or dispensing means such that the stick may be 15 conveniently, yet positively, extruded from or retracted into the container.

One object of this invention is to provide an improved holder, involving relatively rotatable members, one of which constitutes a 20 container for the stick of material, and a carrier movable axially within the container upon relative rotation of said members and provided with means to positively and firmly grip the stick, characterized in that 25 the stick gripping means are releasable when the carrier has been moved to its innermost position to permit extraction of the old and insertion of a new stick into the holder.

Another object of the invention is to provide 30 a holder for stick material, such as shaving soap and the like, which holder is provided with relatively rotatable parts co-operating with an interengaged stick carrier, having means to positively grip and 35 firmly hold a stick of the character mentioned, so that the stick may be positively projected or retracted from or into the holder and so that the stick remains in any position of projection or retraction to which 40 it may be used in the ordinary manner without being itself manually held.

Another object of the invention is to provide 45 in a holder of the general type described, a stick clutching means involving two separable jaws between which the stick 50 may be inserted and which may subsequently be moved toward one another at right angles to the stick's axis to grip the latter, said jaws being automatically held in stick gripping position by the walls of the container within which it is adapted to be drawn.

Another object of the invention is to pro-

vide a holder made up of two relatively rotatable sleeves and a carrier movable within 55 one of said sleeves and arranged to grip the stick of material, one of said sleeves having oppositely disposed cam grooves and the other having oppositely disposed guide slots, the carrier having projections each designed 60 to engage one slot and one groove so that a rotation of one sleeve relatively to the other will move the carrier axially, the construction being characterized in that said projections are yieldable radially to avoid 65 binding in said grooves and to permit convenient assembly and removal of the carrier in the holder.

A further object of the invention is to provide a generally improved holder for material of the character mentioned.

Other features of the invention will appear in the following description and in the illustrative embodiment of the invention in the accompanying drawings, in which:

Fig. 1 is an elevational view, with parts broken away, of a holder embodying the invention;

Fig. 2 is a sectional elevation taken at right angles to Fig. 1 and showing the stick 80 carrier in a different position;

Fig. 3 is a sectional elevational view of the outer casing of the holder;

Fig. 4 is an elevational view of the holder with the outer casing removed (this figure 85 is taken at right angles to Fig. 1);

Fig. 5 is a sectional plan view taken on the line 5—5 of Fig. 2;

Fig. 6 is a sectional plan view taken on the line 6—6 of Fig. 3;

Fig. 7 is an enlarged top plan view of the stick carrier; and

Fig. 8 is a fragmentary sectional elevational view taken on the line 8—8 of Fig. 7.

Referring to these drawings in detail; the 95 holder involves two relatively rotatable casings 10 and 11 which are disposed in closely fitting concentrical relation. One of these casings, as the inner casing 11, is provided with a flanged base piece 12 the periphery 100 of which is preferably knurled to permit the member 12, and thus casing 11, to be turned with one hand while the other casing 10 is held stationary with the other hand. The member 12 is suitably fixed to the lower 105 end of the inner casing 11 and is preferably

of a diameter at least equal to the outside diameter of the outer casing 10, whereby a shoulder or seat is formed for the lower end of casing 10.

- 5 The inner casing 11 is adapted to contain the stick material, such as shaving soap or the like for example. The stick, as *s*, is projectable from or retractable into casing 11 when the casings 10 and 11 are relatively rotated. Thus, the stick *s* is held in a carrier 13 and at opposite points on the periphery of the latter are two projecting pins 14 each of which passes through a slot 15 in the inner casing 11 and into a cam groove, such 10 as the screw thread 16 formed on the interior of the outer casing 10. The two slots 15, as indicated in Fig. 2, are oppositely disposed and extend axially of the casing 11 from points closely adjacent the opposite end of 15 the casing. The grooves 16 consist preferably of helices of relatively small pitch. For example, the two grooves 16 shown are merely a double screw thread, as will be observed from Fig. 3, wherein opposite portions of successive convolutions lie at equal 20 axial distances from the end of the casing. It will be readily understood that when one casing is turned relatively to the other the pins 14 will be moved along the screw 25 threads 16 to move the carrier 13 axially of 30 its casing 11.
- The carrier 13 is specially constructed so as to positively and firmly grip the stick *s* and yet to permit convenient removal and 35 replacement of the stick when desired. To this end the carrier is made up of two semi-cylindrical sections 17 and 18 which, as indicated in Fig. 4, normally are held in substantially abutting relation by the cylindrical 40 wall of casing 11. A hollow tubular member 19 passes diametrically through the mating sections 17 and 18 and is preferably suitably held, as by friction, to one section, as 45 17, the other section, as 18, being readily movable on the member to permit separation 50 of the sections. The member 19, as best shown in Fig. 8, supports the described pins 14, by means of which the carrier 13 is moved within its casing 10. Such pins 14 55 are mounted to yield axially and to this end a spring 20 is provided within member 19 which tends to force both pins 14 axially outwardly to the extent permitted by the abutment of the flanged heads of the pins 60 with the "crimped in" portions of member 19. One of the sections, as 18, is provided with a shouldered down portion 21 (Fig. 2) which, when the carrier 13 is moved outwardly from casing 11 to the limit (as defined by the abutment of pins 14 with the upper ends of slots 15), permits the section 65 18 to be moved radially away from the section 17 without in any way necessitating removal of the carrier 13 from the casing 11. Each of the sections 17 and 18 are provided

with suitable means to grip the stick *s*. Thus, each section is provided with a relatively thin semi-circular upstanding wall 22 to encompass the stick *s*, the base of which is of course supported on the upper faces of 70 the sections 17 and 18. At intervals around the periphery of the walls 22 projections 23 are provided, as shown in Figs. 7 and 8, which projections will dig into and firmly grip the stick *s*, when the two sections 17 75 and 18 are pushed together. The upper edge of each wall 22 may be slightly turned over, as shown in Figs. 7 and 8, to produce very small flanges 23' which aid in gripping the stick *s*.

80 In order to permit the described elements to be conveniently assembled or taken apart, when desired, there are provided certain other desirable constructional features, as will now be described. The outer casing 10 85 is, as shown in Fig. 3, provided with a vertical groove 25 which extends from the lower terminus of one helical groove 16 to the lower end face of casing 10. As indicated in Fig. 6, there is a second similar groove 90 25' for the other helical groove 16 and the two grooves 25 and 25' are arranged in diametrically opposite relation. Thus, when the carrier 13 has been moved inwardly as far as possible, both pins 14 will be alined with 95 their respective slots 25 and 25' so that the outer and inner casings 10 and 11 respectively may be separated by moving one relatively to the other in an axial direction.

Any suitable means may be provided to restrain the casings 10 and 11 from relative movement in an axial direction. One simple and advantageous means, at present preferred, involves the provision of at least one projection 27 (Figs. 1 and 4) which is arranged to ride in a circumferential groove 28 (Figs. 2 and 3) to prevent separation of the casings. Preferably, although not necessarily, the projection 27 is arranged vertically in line with one of the slots 15, as indicated in Fig. 1. By this arrangement, one of the described slots, as 25', may be utilized to receive the projection 27 and permit its passage to the groove 28. The other slot 25 is preferably made slightly smaller than projection 27, the arrangement being such that each of the slots 25 and 25' is capable of receiving the pins 14, but only one, as 25', is capable of receiving projection 27. The arrangement just described permits the axial separation of the casings 10 and 11 whenever the carrier 13 has been moved to its innermost position for then both pins 14 must necessarily aline with their respective slots 25 and 25' and so also the projection 27, which is located in line with one slot 15; and thus with one pin 14, must aline with its groove 25'. At all other positions of the carrier complete separation of the casings is not permitted, for although projection 27

may periodically align (once each revolution) with its groove 25', the pins 14 obviously prevent removal of the outer casing 10. This arrangement, for retaining the casings 10 and 11 in assembled relation, is considered an important and advantageous feature of the invention.

Another most important feature of the invention consists of the yieldable cam followers or pins 14. A single rigid pin of exactly the right length could of course be used, but, should the grooves 16 become the least bit gummed up or should the pin project slightly farther from one than from the other side of the carrier 13, a binding action would result. The described yieldingly mounted pins 14 avoids this difficulty and yet insure a certain engagement with the necessarily shallow cam grooves 16 at all times. The pins 14, also permit the carrier 13 to be readily inserted into or withdrawn from casing 11, when desired. After the removal of casing 10, as already described, the pins 14 are accessible as shown in Fig. 4 and if the carrier is moved to its outermost position and both pins 14 pressed inwardly to clear the inner wall of casing 11, the carrier 13 may then be readily withdrawn. The assembly of the carrier 13 in casing 11 involves merely a reversal of the described operations.

A most essential feature of the present invention consists of the arrangement whereby the stick can be removed from or replaced in the holder without taking the holder apart. This result is important in a holder of the present character wherein means are provided to positively clutch the stick so that it can be moved positively in either direction. As distinguished from mere adhesion or frictional engagement, the described arrangement provides positive means to clutch, grip and dig into the sides of the stick so that it is firmly held to the carrier without leaving space sufficient for stick *s* to wobble. The projections 23 act as jaws and dig into the stick from opposite sides and at right angles to its axis.

In use, the casing 10 may be held stationary while the member 12 is turned until the carrier 13 has been moved into the position shown in Fig. 2. The two parts of the carrier 17, and 18, may then be spread apart to receive the stick *s* and thereafter closed together to grip the stick without serious abrasion. The member 12 is then turned in an opposite direction until the stick *s* has been wholly drawn into its container 11. Thereafter, the user merely turns the member 12 to project stick *s* sufficiently for use and after use retracts the stick within the casing. The pitch of grooves 16 is purposely made such that the stick is retractable only by turning the casings 10 and 11, the one relatively to the other. That is a push on the

stick *s*, as when it is pressed against the face in normal use, will not retract the stick.

It is also to be noted that the stick *s* has no rotary movement with relation to its contiguous casing 11. This is important in that it prevents "shaving" of the stick as would otherwise happen if the stick continually turned past the edges of the slots 15. Such "shaving" action soon results in gumming up the interior of the casing and produces undesirable unsanitary conditions. The arrangement of the vertical guide slots in the inner casing, rather than providing the cam slots 16 of many convolutions therein, is also important for similar reasons.

The invention has been disclosed herein for illustrative purposes, but the scope of the invention is defined by the appended claims rather than by the foregoing description.

80

85

What I claim is—

1. In a holder for stick material, a casing to contain the stick, a carrier movable axially in said casing, a member rotatable relatively to said casing, co-operating and interengaging means provided on the carrier, casing and member to move the carrier when the casing and member are relatively rotated, and clutching means on said carrier to positively grip the stick, said means being separable when the carrier is moved to its outer position in said casing to permit extraction or insertion of a stick.

2. In a holder for stick material, a casing to contain the stick, a carrier movable axially in said casing, a member rotatable relatively to the latter, co-operating and interengaging means provided on the carrier, casing and member to move the carrier axially in the casing when the latter and said member are relatively rotated, oppositely arranged jaws on the carrier to positively grip the stick, said jaws being held in stick gripping position at all times, except when the carrier is moved to a predetermined position in which said jaws are separable to release the stick and permit its removal and the insertion of a new stick.

3. In a holder for stick material, two relatively rotatable tubular casings positioned one within the other in substantially contiguous and concentrical relation, oppositely arranged cam paths provided in one of said casings, oppositely disposed longitudinal guideways provided in the other of said casings, a member extending diametrically across the inner casing and provided with projections at opposite ends to engage said cam paths and guideways, and a split cylindrical element carried by said member and having two sections separable axially of said member, stick gripping means carried by each section and normally held in gripping position by the wall of said inner casing, said element being movable axially in

115

120

125

129

the casing by relative rotation of said members and movable to a predetermined position in which said sections may be separated.

4. In a holder for stick material, relatively rotatable tubular casings positioned one within the other in concentrical relation, oppositely disposed cam paths provided in one of said casings, oppositely arranged longitudinal guideways provided in the other casing, a carrier within the inner casing to which the stick may be attached, oppositely arranged projections on the carrier arranged to engage said cam paths and guideways, and means permitting said projections to yield radially of the carrier.

5. A holder for stick material, comprising, a casing to contain the stick and provided with oppositely disposed longitudinal slots therein, means attachable to the stick and having projections passing through said slots, an outer casing revoluble relatively to the first-named casing and having oppositely disposed helical cam grooves in which the ends of said projections are received, and longitudinal grooves leading from the inner ends of said helical grooves to the inner end of the outer casing, said longitudinal

grooves permitting the removal or replacement of the outer casing by receiving said projections from or for said helical grooves. 30

6. A holder for stick material, comprising, a casing to contain the stick and provided with oppositely disposed longitudinal slots therein, means attachable to the stick and having projections passing through said slots, an outer casing revoluble relatively to the first-named casing and having oppositely disposed helical cam grooves in which the ends of said projections are received, and longitudinal grooves leading from the inner ends of said helical grooves to the inner end of the outer casing, said longitudinal grooves permitting the removal or replacement of the outer casing by receiving said projections from or for said helical grooves, 35 a circumferential groove in the outer casing intersecting one of said longitudinal grooves, and a fixed projection on the inner casing in line with one of the first-named projections and arranged to ride in the circumferential groove and prevent removal of the outer casing. 40 45 50

FRANK GRANT.
